UNITED STATES PATENT OFFICE.

SAINT VRAIN LE SIEUR, OF EAST ST. LOUIS, ILLINOIS, ASSIGNOR TO THE LE SIEUR VACUUM CAN MANUFACTURING COMPANY, OF EAST ST. LOUIS, ILLINOIS. A CORPORATION OF ILLINOIS.

MILK-CAN.

1,075,834.

Specification of Letters Patent.

Patented Oct. 14, 1913.

Application filed July 3, 1911, Serial No. 636,697. Renewed February 18, 1913. Serial No. 749,279.

To all whom it may concern:

Be it known that I, SAINT VRAIN LE SIEUR, citizen of the United States, residing at East St. Louis, in the county of St. Clair 5 and State of Illinois, have invented certain new and useful Improvements in Milk-Cans, of which the following is a full, clear, and exact description, reference being had to the accompanying drawings, forming a part 10 hereof.

My invention has relation to improvements in milk-cans; and it consists in the novel construction of can more fully set forth in the specification and pointed out in 15 the claim.

In the drawings, Figure 1 is a half vertical section and half elevation of a milk-can showing my invention applied thereto; Fig. 2 is an elevation of the outer cover detached; 20 Fig. 3 is a bottom plan with parts broken away; and Fig. 4 is a horizontal section on the line 4—4 of Fig. 1.

The object of my invention is to construct a milk-can which will be proof against 25 changes of temperature, thus permitting the contents to be preserved against possible fermentation and souring.

A further object is to provide a can which is strong, durable, and comparatively cheap 30 to construct; and one possessing further and other advantages better apparent from a detailed description of the invention which is as follows:—

Referring to the drawings, 1 represents 35 the outer section or member of the can, and 1' the inner section, being thus practically a can within a can, the two sections being separated by a space α from which the air may be exhausted. The upper ends of the 40 necks n and n' of the respective sections are held apart by a ring 2 of asbestos or other heat non-conducting material, which is (in any common and well known manner) im- 45 pregnated with paraffin wax and compressed and hardened to render the said ring im- pervious to air, after which said ring is cemented securely within said space, and thus seals the space α at that point. Distributed along the bottom of the inner can or section 50 1' are spacing angle brackets 3 with their legs secured respectively to the bottom of the section 1' and to the side walls of the outer section 1, a strip or layer of asbestos or other heat non-conducting material 4 be- 55 ing interposed between the wall of the sec-

tion 1 and the bracket legs. The opening of the neck of the double can is closed by a metal lid 5 having an upper marginal flange 6 resting on the upper edge of the double neck and extending over the ring 2. The lid 5 is preferably dished and is provided with a rib 7 disposed in the plane of the flange 6, said rib serving as a handle. The lid 5 is protected by an outer cover 8 provided with a depending flange or rim 9, said rim having formed therein at diametrically opposite points the angular recesses 10, the legs of which coöperate with studs 11 disposed on the outer surface of the neck n . By passing the rim 9 of the cover over the 70 neck n in such a way as to cause the studs 11 to enter the vertical legs of the recesses, and then giving the cover a partial rotation so as to cause the studs to enter the horizontal legs of the recesses, the cover will be effectively locked. This locking means however, is not new nor is the same claimed herein specifically. The cover is provided with an asbestos or equivalent layer 12 of 75 heat-non-conducting material as shown. 80

The can in the present case has a raised bottom, the outer layer (or bottom of the outer can) being provided with an outwardly-opening check-valve V, preferably of the hinged variety, the same being surrounded 85 by a screw-threaded nipple 13 to which the hose (not shown) leading from any suitable suction pump or exhauster may be temporarily attached to exhaust the air from the space α between the two sections of the can. 90 Once the air is exhausted, the nipple 13 is, in a common and well known manner, covered over with a seal of soft solder 14 to protect the valve from injury. The solder may be removed at any time should 95 occasion arise to exhaust the air on account of leaks. The rarefied air or vacuum in the space α being a non-conductor of heat, and the asbestos layers 4 and 12 being likewise non-conductors, it follows that changes in 100 temperature of the outside air can not affect the contents of the can, and thus the milk remains sweet and fresh until disposed of. The solder 14 when in position, does not project beyond the plane of the bottom 105 edge of the can, and thus can not be broken off in the handling of the can. Though denominated as a milk-can, the vessel may obviously be used for cream, and other liquids likely to ferment or sour under favorable 110

temperatures. The purpose of the lid 5 is to prevent the milk or cream from saturating the asbestos lining of the outer cover.

In lieu of the brackets 3, or in conjunction with the same, I may employ asbestos spacing plugs 15 between the side walls of the two can sections. In the event that the spacers 3 are dispensed with, and the members 15 are used alone, care should be taken 10 to provide a tight fit between them and the walls of the sections 1, 1', so that the inner section shall not drop to the bottom of the outer section. Obviously, the bottom of the outer section is seamed to the walls of said 15 section, after the inner member 1' is in its proper position and otherwise secured to the outer section.

Having described my invention, what I claim is:—

20 A milk-can comprising an outer section or

member, an inner section spaced from the outer section, brackets projecting from the bottom of the inner section and engaging the outer section, strips of heat-non-conducting material interposed between the brackets 25 and the inner surface of the outer can-section, a neck for each section, a sealing ring fixed securely in the space between the ends of the neck portions, an outer cover for the necks provided with a layer of heat-non- 30 conducting material, and means for connecting the space between the sections with a suitable vacuum pump.

In testimony whereof I affix my signature, in presence of two witnesses.

SAINT VRAIN LE SIEUR.
